UNITED STATES PATENT OFFICE.

CHRIS S. VAN HORN, OF BLOOMSBURG, PENNSYLVANIA.

ELECTRIC PNEUMATIC CASTING MACHINE.

Application filed July 27, 1920. Serial No. 399,365.

To all whom it may concern:

Be it known that I, CHRIS S. VAN HORN, a citizen of the United States, residing at Bloomsburg, in the county of Columbia,

5 State of Pennsylvania, have invented certain new and useful Improvements in Electric Pneumatic Casting Machines, of which the following is a description, reference being had to the accompanying drawing and to the figures of reference marked thereon.

This invention relates to dental castings, and more particularly to an improved apparatus used in connection with my process for producing dental inlays of exact 15 dimensions.

Up to the present time, no apparatus has been devised for the accurate casting of dental inlays, that is, dental castings of the same marginal dimensions as the wax pattern in the tooth. The methods and apparatus now in use are at best, only approximate, mainly because no cognizance is taken of the fact that the materials which enter into the casting operation, such as the gold, 20 the investment materials, and the pattern waxes, are subject to the physical law of expansion and contraction upon the application and withdrawal of heat, each such substance having its individual coefficient 25 under varying thermal influence.

For instance, in all known processes, no exact allowance has been made for any change in size in the wax pattern occurring in transferring it from the mouth to the investment. Pattern wax is very susceptible 35 to the physical effect of heat, a rise or fall of a few degrees in temperature during the hardening or setting of the investment involving the pattern, means a corresponding 40 change in the size of the wax mass and consequently the casting cavity or mold. So also, during the drying out and burning out operations the investment expands when heated to such high temperatures as 1,000° 45 F., which expansion produces a corresponding increase in the size of the casting cavity.

An accurate process demands not only that the investing apparatus used be capable of not only imparting through the 50 plastic investment a given temperature to the wax pattern during the investment and maintaining this definite temperature until the investment is thoroughly hardened, but also that the casting apparatus be capable of imparting to the investment which forms the casting mold, a predetermined elevated tem-

perature whereby to slightly enlarge and maintain at such size, the casting cavity in the investment during the drying out, burning out, and even during the initial portion 60 of the actual casting operation. This temperature regulation must be accurate, and at all times under the absolute control of the operator.

To make a gold casting of the same marginal dimensions or size as the wax pattern, when the latter is in the tooth cavity in the mouth, the wax pattern must be invested at a temperature sufficiently above 70 tooth cavity temperature (which is approximately 95° F.) to compensate for the shrinkage in the gold casting during its cooling.

Present pattern waxes of the best quality can not be safely expanded in excess of 75 about two per cent without melting or dulling delicate or sharp margins of the pattern, and investing materials of the best quality have a maximum expansion of 0.85 per cent at around 1000° F. Above this they shrink 80 that is, burn smaller, and if permitted to cool down from 900° to 70° F., they shrink, and the mold is smaller than when the investment set. On the other hand, the total shrinkage in 24 K. gold is around 3.84 per 85 cent, which can be partly controlled by pressure, when casting, but the uncontrollable shrinkage in gold when cast under high pressure is 2.20 per cent. Hence, in order to neutralize all this uncontrollable shrinkage 90 in the gold, that is, 2.20 per cent, some means other than the expansion of the pattern must be used. The expansion of the investment when heated to dry out and burn out the wax is availed of. Minimum gold shrinkage 95 (2.20 per cent) minus maximum wax expansion (2 per cent) leaves 0.20 per cent shrinkage to be neutralized through the investment expansion which is 0.85 per cent maximum.

100 The most rational technique is therefore to utilize the maximum expansion of the investment without disintegrating it by maintaining the mold, and hence the contained investment at an elevated temperature during the drying out and burning out periods, and to supplement this expansion with a correspondingly less than maximum expansion of the wax pattern during the investing process, so that these combined expansions of the pattern wax during investing and the expansion of the in-

vestment during drying out and burning out, produce a mold or casting cavity of just the right size so that the gold cast therein will on cooling, contract to the same marginal dimensions as the original wax pattern when in the tooth cavity in the mouth.

By a series of experiments and calculations, taken in connection with this method of casting, it has been found that the 10 wax pattern should be maintained at an approximate temperature of 115° F. during the investment operation, and that the investment, should be subjected to a maintained temperature of about 900° F. during 15 the drying out, the burning out and initial part of the casting into temperature.

This method thus takes into consideration the individual contractions and expansions of the pattern, of the investment and of the 20 gold casting during the process of making the dental inlay, and by controlling the heating effects throughout the entire process, produces a casting of the required marginal dimensions.

25 Inasmuch as the present invention relates solely to the casting apparatus used in connection with the above process, no further mention of the investment apparatus will be made, the same forming the subject matter of a separate application.

In all prior appliances, there was no means of knowing or even approximately guessing the temperature at which the investment was dried out, the wax burned 35 out, and of the gold at the moment the gold was cast into it. In the present apparatus, these temperatures are known, and are at all times under the control of the operator, thus materially simplifying the casting process, 40 since any number of castings may be executed under essentially the same temperature conditions.

The main object of this invention is to provide a muffle and flask mechanism constructed and arranged to suitably control the temperature of the investment during the drying out, and burning out and casting 45 operation.

Another object of the present invention 50 is to provide a device of the character described which comprises a flask seat and a suitably heated muffle, together with means for shifting the muffle and seat relatively so that the seat supporting the flask with its 55 contained investment can be moved within or without the muffle.

Still another object of this invention is to provide a device of the character described which includes an electrically heated muffle, 60 a flask seat carriage movable within the muffle chamber, together with means for controlling the heating effect of said muffle and regulating the temperature thereof at any instant.

65 Still another object of the invention re-

sides in providing a device in which the flask seat in moving outside of said muffle chamber automatically acts to alter the heating effect of the muffle.

Still another purpose of this invention 70 is to provide an improved muffle for a device of this character in which the muffle is formed with an open chamber around the inner walls of which is arranged a heating coil, the muffle being constructed 75 so that the flask seat in its movement within the muffle will take a position so that the heating wires will entirely surround the same.

A further object of this invention is to 80 provide a muffle of improved construction for use in the above mentioned arrangement.

A further object of this invention resides 85 in providing a novel arrangement of a muffle, and flask seat carriage adapted to move the flask seat supported thereby into the muffle chamber, the flask seat carriage and flask seat being suitably vented to permit the escape of gases and other matter during the drying out and burning out operations. 90

Still another object of this invention relates to the specific construction of the flask seat itself.

Another aim of this invention is to provide a novel combination and arrangement 95 of muffle, flask seat and its supporting means, and flask seal mechanism whereby the flask seat supporting means with its flask and contained investment may be shifted from a position within the muffle 100 into contact with the flask seal mechanism.

Yet another object of this invention comprises the means for automatically locking the flask seat supporting the flask and contained investment in contact with the flask 105 seal.

A further object of this invention resides in providing a flask seat and flask seal with means for shifting said seat and seal relatively, whereby to contact the flask on the 110 seat against the seal, together with means for locking the said parts in such position, and means for admitting fluid pressure to the investment within the flask during the casting operation.

A further object of this invention resides 115 in the means whereby the relative movement between the flask seat and seal control the air pressure admitted to the investment in the flask.

Another feature of the invention resides 120 in the novel construction of the upper edge of the flask which is adapted to contact against the seal mechanism to maintain an air tight joint.

Still another feature of the invention resides 125 in an improved sprue construction.

These and other objects will in part be obvious and will in part be hereinafter more fully disclosed.

Referring more particularly to the accompanying drawings:

Figure 1 illustrates a perspective view of the entire machine;

5 Fig. 2 is a fragmentary sectional view illustrating particularly the muffle, the flask seat mechanism, and the flask seal;

Fig. 3 is a sectional detail of the sprue;

Fig. 4 is a bottom view thereof, and

10 Fig. 5 is a detail sectional view of the flask seat.

Broadly, the invention comprises the supporting standard on which is mounted a muffle provided with a preferably vertically arranged bore therethrough, the inner walls of which are formed with heating coils entirely around the same, with electrical connections to a thermo-electric couple and the usual pyrometer which is also mounted on the base. The heating effect of the muffle is controlled by means of the usual rheostat likewise mounted on the base. Vertically movable through the axis of the muffle bore is arranged the flask seat carriage adapted 25 to support the flask seat, on which is placed the flask with its contained investment, so that when the flask is lowered into the muffle, it will be entirely surrounded by the heating coil. Arranged in spaced relation to the end in line with the bore of the muffle is a flask seal mechanism provided with suitable connections to a source of preferably compressed air, and the arrangement of the muffle, the flask seat and flask 30 seal is such that the flask seat may be shifted from a point within the muffle chamber into sealed contacting position, the apparatus being constructed and arranged so that when in this latter position, the flask seat is locked 35 against shifting movement and air pressure is admitted from a tank into contact with the investment within the flask.

Referring more particularly to the accompanying drawings, there is provided the 40 usual base 1 of suitable insulated material, upon which is mounted by means of the standards 2, 3, a suitably formed support 4, to the front end of which is preferably removably attached a muffle 5. As shown 45 more in detail in Fig. 2, the forward end of the supporting base 4 is provided with a suitable upstanding flange 6 within which is mounted a bushing flange a tubular support 7, which flange, together with the flange 6, forms a support for the muffle. While 50 the muffle may be of any desired shape, and construction, the preferred form comprises an annulus of suitable heat resisting material 8 around the inner periphery of which 55 is continuously wound a heating coil 9, the upper and lower loops of which are suitably embedded in the upper and lower end walls of the annulus 8 by means of any desired fastening means 10. The base and 60 top end caps 11 and 12 are provided for

covering the exposed ends of the annulus and winding. As shown in the drawings, these caps 11 and 12 are suitably cut away as at 13 to clear the winding wires. The upper cap 12 is provided with a central 70 beveled mouth 14 terminating in a projecting lip 15 which forms a suitable opening for the entrance of the flask into the muffle chamber. The base cap 11 is likewise cut away and is provided with a central bore 75 16, the walls of the cap at this point being suitably conformed to provide a supporting surface for the muffle to seat itself upon the upstanding flanges 6 and 7. If desired, an additional bracket may be provided as at 80 17 for attaching the muffle to an upwardly projecting standard 18, which in the present case, is shown as integral with the support 4 on the base. The muffle is provided with a thermo-electric couple 19 and with suitably insulated connections 20 to the pyrometer 21, illustrated in Fig. 1, which at all times records the temperature of the heating coil. The heating effect in this coil is controlled by the usual rheostat mounted preferably on the base 1 including the movable arm 22 making contact with a series of resistance contacts 23. The machine is adapted to be connected to an external source of current connected to one contact 22' and to 85 the other contact 23' of the knife switch 24', so that by manually opening and closing this switch, current to the machine is cut out or in. In addition to this manual control cut off, there is arranged an automatic cut off comprising an arm 25' attached to the base of the flask seat carriage hereinafter described and adapted to be raised by the elevation of the flask seat carriage to 90 throw the knife switch 24' and break the 100 connection.

The investment contained within the flask is adapted to be heated to the desired temperature by means of the muffle and in order to introduce the flask within the 110 muffle, there is provided a relative shifting movement between the flask carriage and muffle. The preferred construction for accomplishing this function is shown in the present apparatus, in which the forward 115 part of the base 4 is provided with a vertical bore 24 concentric with the axis of the muffle and the upstanding flanges 6 and 7. Movably mounted within this bore is arranged a flask seat carriage, preferably in 120 the form of a plunger 25 provided along its inner lower extremity with the gear teeth 26 (see Fig. 1), meshing with a pinion 27 mounted on a shaft 28 having bearings 29 and 30 depending from the under side of 125 the base 4. The outer extremity of the shaft 28 is provided with a suitable handle 29' for giving oscillation to the shaft to raise and lower the flask seat carriage.

130 The flask seat 31 for supporting the flask

32 upon the carriage, in the preferred form, is adapted to detachably seat in the upper end of the plunger 25. This is accomplished by forming the upper end of the plunger as a hollow tube into which fits the flask seat 31 which is provided with a tubular shank 33 and a laterally extending annular supporting surface 34 formed with an upstanding flange 35 to form a supporting rim fitting snugly within the free end of the flask 32. This upstanding rim is adapted to seat a wafer of porous material for a purpose hereinafter described. This rim 35 is provided with vertical slits 35' therearound to permit the escape of the gases from within the flask and likewise the base 34 of the seat is provided with suitably formed vents 36, and for the same purpose, the shank 33 is provided with a central bore opening on to the supporting surface of the base 34. If desired, the hollow shank 33 may be provided with suitable additional vents 37 for a similar purpose so that when the shank 33 of the flask seat is fitted within the hollow end of the carriage 25, and the flask with its contained investment is seated on the flask seat, within the muffle, and the heat generated to burn out the wax pattern within the investment, the gases, smoke and moisture from the pattern can escape through the porous insert in the flask seat, through the vent slits 35' in the upstanding rim 35, through the perforations 36 in the base 34, through the bore 38 of the shank 33, and through the vents 37 into the hollow end of the plunger 25, which is also provided with suitable vents 39 for the discharge of these gases, out through an opening 40 in front of the support 4.

Arranged above the muffle 5 and in axial alinement therewith, is a flask seal mechanism. This mechanism is preferably supported on the standard 18 and comprises a chambered sealing head 42 secured on the standard 18 and overhanging the muffle. Movable mounted within the chamber 43 on the lower portion of the base 41, is a flask seal comprising a plunger 44 formed with an enlarged annular face 45, peripherally threaded to receive a flange 47 adapted to hold in place a yieldable packing or flask contacting member 48 which is composed of suitable material capable of forming an air tight seal with the upper rim of the flask, which as shown in detail in Fig. 3 is provided with an annular rounded bead 75, which not only insures an air-tight joint at this point, but prevents the packing 48 from being cut by the pressure of the locking mechanism hereinafter described. The plunger 44 is provided with a central bore 45 and projecting nozzle 46 forming an air outlet. The inner end of plunger 44 slides within the chamber 43 in the head 41, and

the end 49 thereof forms a suitable abutment adapted to back up against a substantially rigid connection 50 held within the upper end of the chamber 43 by means of a plug 51 having threaded connection with the inner hole of the head 41. This plug 51 is likewise provided with a centrally arranged bore 52 forming an air conduit in axial alinement with the air conduit 45 and connecting chamber 43 with an upper chamber 53 in the upper portion of the head 41. This chamber 53 is provided with a suitable connection 54 to a source of air or fluid pressure 55. The connection between the air conduit 52 and chamber 53 is controlled by an air valve 56 provided with a preferably integral stem 57 sliding in a bore 58 formed in a cap 59 threading into the outer extremity of the head 41. A suitable spring 60 normally seats this valve. Projecting through the threaded plug 51 is an adjustable push rod 61, the upper end of which contacts firmly against the under face of the valve seat, while the lower end of this push rod 61 is provided with an adjustable threaded connection 62 with a similarly threaded inner face of the plunger 44, said connection being suitably ported as at 63 to permit the passage therethrough of the compressed air. The flask supported on the flask seat in its movement upward, contacts against the flask seal to slightly move the same, thereby admitting compressed air into the flask, and in connection with this construction there is also arranged mechanism for positively and automatically locking the flask seat in this raised seal contacting position. This last named function is accomplished by providing the lower portion of the carriage or plunger 25 with a suitably formed slot 64 adapted in the raised position of the carriage to come abreast of a locking member 65 slidably mounted within the bore 66 in the support 4. As shown in Fig. 2, this locking member 65 is surrounded by a spring 67 coiled between an abutment 68 on the locking member and the cap 69 secured to the base so that the spring tends to force the locking member 65 into the slot 64 when in alinement therewith. In order to retract the locking member 65, the same is provided with teeth 70 at its outer end gearing with a pinion 71 on the shaft 72 controlled by an oscillatable lever 73. In order to retain the plunger 25 with its slot 64 in suitable alined position, a key-way 74 is provided on the base of the plunger 25 adjacent the plunger, so that when the plunger is in lowered position the locking member 65, will project slightly into the key-way 74 to act as a spring pressed retaining means to hold the plunger 25 in any shifted position. The lower face of this key-way is provided with a gradually sloping surface so that the locking member 65 will be forced

freely backwardly on the further elevation of the carriage 25. When the flask on the flask seat is raised into contact with the flask seal 48, it is thereafter necessary to 5 make this contact air-tight, so that the air pressure thereafter admitted through the seal into the flask will not escape and to accomplish this, it is necessary to securely lock the flask seat against downward movement 10 prior to the introduction of the air pressure. In order to accomplish this, the upper face of the locking member 65 is provided with a cam surface 65' which, when the locking member is projected into the slot 64, 15 acts to give the plunger 25 an additional lifting movement into extreme upper position, at which time, the locking member 65 has passed entirely through slot 64 under the action of the spring 67. This additional 20 upward movement is permitted by the yielding movement of the plunger 44 of the sealing head.

The special form of sprue used in connection with the improved process set forth 25 in this application is shown in Figures 3 and 4. In this connection, the sprue comprises a base 76 provided with an annular flat lateral rim 77 and an inner upstanding flange 78 adapted to fit exactly within the 30 inner periphery of the flask as therein shown, the end of the flask resting on the annular supporting surface 77. The upstanding flange 78 is integral with a central conical projection 79 formed with a longitudinal bore 80. The base is likewise provided with a plurality of spring fingers 81 which project laterally from the plane of the surface 77 to engage the outer periphery of the flask 32 whereby the same is held securely 35 between the spring fingers 81 and the upstanding flange 78, the end of the flask being as before stated, supported permanently on the seat 77. These fingers 81, of which there may be three or more, are 40 secured to the base member by means of a threaded cap 82 screwing into a suitable recess 83 in the base. Obviously, other modes of forming these fingers and attaching them to the base may suggest themselves. Longitudinally within the central 45 bore 80 of the base is a sprue wire 84 which, as shown in the drawings, is adapted to hold the wax pattern 85 in proper position within the contained investment 86. Means is 50 provided for holding this sprue wire in adjusted position, herein shown as a threaded member 87 passing transversely through the threaded cap 82 and engaging the sprue 84. This adjusting member 87 is provided with 55 a thumb piece 88 to facilitate its turning.

For a complete understanding of the present invention, it is explained that after the pattern is formed in the usual manner and placed on the sprue 84, and after 60 the investment material has been mixed,

the pattern and the investment material are subjected in the investing apparatus to a maintained temperature of approximately one hundred and fifteen degrees F. The pattern is now quickly given 70 the usual preliminary coating and is then placed in the flask to the proper depth by means of the adjustable sprue 84, and the investment introduced around the pattern care being taken to provide a uniform 75 temperature throughout the entire investment process. While it must not be overlooked that when the investment is being poured into the flask and when the pattern is coated, a change in temperature takes 80 place. This change, even though pronounced, is corrected by employing a slow setting investment which does not begin to stiffen under five minutes or more from the time when it is poured into the flask, thus 85 allowing ample time for it to regain the loss and impart to the wax the desired determinable temperature, the ultimate desideratum being the temperature of the wax 90 during the setting of the investment.

The flask having remained for possibly one-half hour at a constant temperature, the investment has then hardened sufficiently to resist any change in the size of the pattern due to change in temperature, and so is 95 transferred after removing the sprue and smoothing the crucible in the usual way to the casting apparatus which forms the subject matter of the present invention for the drying out, the burning out, and the casting 100 operation.

The flask with its contained investment having been placed upon the flask seat in the casting machine, and lowered into the electric muffle 5 by rotating the hand lever 105 29 counter-clockwise, the electric current is then turned on by closing the switch 24', the rheostat control lever 22 being on the proper contact. By means of the thermoelectric couple which is in the muffle chamber, and connected to the pyrometer, the degree of heat which is generated in the muffle is recorded on the pyrometer scale, and by means of the rheostat, the temperature of the muffle is under complete control so that 110 the drying out and burning out operations may be completed at the exact temperature demanded.

After this operation, the temperature is raised to the desired degree for a sufficient length of time, a given quantity of gold metal is then placed in the ingate and is then very quickly brought to the desired state of liquefaction by the direct application of an oxyhydrogen jet. Prior to this heating the lever 29 is shifted clockwise to lift the flask out of the muffle, and during this upward movement, the finger 25' on the base of the plunger 25 has struck the knife switch 24' to break the electric circuit to 120 125 130 135 140 145 150 155 160 165 170 175 180

the heating coil so that thereafter the gold in the ingate is heated solely by the oxyhydrogen jet. At the moment the bead 75 on the top of the flask seat 32 contacts with 5 the flask seal 48, the lowest point on the top face of locking key 65 is in register with the upper edge of the slot 64 in plunger rod 25, hence the compression spring 67 is free to act so that the cam face 65' of the locking member 65 under actuation of the spring 10 forces the flask and flask seal base 48 and flask seat upwardly until the flask seal base plunger 49 meets the fixed packing 50. Just a fraction of a second after the seal head 15 starts to move the valve, the push rod 61 contacts with air valve 56 and lifts it off its seat, thus admitting compressed air through the passages 45, 63, chamber 43, conduit 51, chamber 53, and inlet 54 into the 20 flask and the ingate and forcing the fluid metal into the mold in the investment. The force exerted by the cam face 65' of the locking pin actuated by the spring 67 against the top of slot 64, is transmitted through 25 carriage 25, thus automatically establishing an air-tight union between the bead 75 on the flask 32 and the flask seal 48 to securely lock the moving parts in that fixed position.

After the metal casting has crystallized, 30 the flask is released by turning the lever 29 clockwise and the locking pin 65 is withdrawn by means of the oscillation of the handle 73 after which the flask may easily be lowered to any desired position by turning pinion 27 by means of the handle 29. Furthermore, the front face of the tapered locking pin 65 when not in slot 64 engages 35 with the key-way 74 on the carriage 25, and while the carriage 25 may be easily raised or lowered to any position desired other 40 than that to the position of the flask contacting with the sealing mechanism, it will remain automatically at that particular position for the reason that the end of the 45 locking pin is forced by the spring 67 against the key-way of the carriage.

It is also obvious that many changes in the details of the construction and the arrangement of the parts may be made without departing from the spirit of the invention as set forth in the appended claims.

Having thus described the invention, what I claim as new and desire to secure by Letters-Patent, is—

55 1. An electric pneumatic casting machine comprising a base, an electrically heated muffle thereon, a flask seal mounted on said base adjacent said muffle, means providing a source of air pressure for said seal, a flask seat adapted to support a flask with its contained investment, normally mounted on said base and adapted to be shifted into said muffle or into contact with said seal to receive air pressure therefrom, a thermo- 60 electric couple and pyrometer mounted on 65

said base and electrically connected to said muffle for controlling and recording the heating effect thereof, a rheostat mounted on said base for regulating the heating effect of said muffle, and means operable by 70 the movement of said flask seat for controlling the muffle heating circuit.

2. An apparatus of the class described comprising a support, an open-top muffle mounted thereon, a flask seat on said support adapted to receive a flask and its contained investment, means constructed and arranged to shift said muffle and seat relatively to position said flask either within or without said muffle while maintaining 80 the investment constantly accessible.

3. An apparatus of the character described comprising a support, a muffle mounted thereon, means for controlling the temperature of said muffle, a flask seat mounted on said support adapted to seat a flask and its contained investment, means for relatively moving said seat and muffle to position the flask within or without the muffle and means for automatically holding said muffle and 90 seat in relatively shifted position.

4. An apparatus of the character described comprising a base, an open-end muffle mounted thereon with the open end 95 uppermost, a flask seat mounted on said base and adapted to support a flask with its contained investment, and means projecting through the lower end of the muffle for raising and lowering said flask into and out of said muffle whereby said investment is constantly accessible.

5. An apparatus of the character described comprising a base, a muffle thereon, means for heating said muffle, a flask seat mounted on said base, adapted to support a flask with its contained investment, means for moving said flask seat and muffle relatively, and means acting at a certain period in said movement to control the effect of 105 said heating means.

6. An apparatus of the character described comprising a base, a muffle thereon, means for heating said muffle, a flask seat on said base adapted to support a flask with its contained investment, means for moving said seat within and without said muffle, said means acting to control said heating effect when said flask seat is moved away from said muffle.

7. An apparatus of the class described 120 comprising a tubular support, an open-ended muffle mounted thereon, a flask carriage shiftable through said tubular support, a flask seat on said carriage for supporting an investment, and means for shifting said carriage to position said flask seat within and without said muffle.

8. An apparatus of the class described, comprising a support, a muffle mounted thereon, a flask carriage shiftable on said 125

support, a flask seat on said carriage, means for shifting said carriage, and a spring pressed detent normally engaging said carriage to hold the same in shifted position.

5 9. A device of the character described comprising a tubular support, an open-ended muffle mounted thereon, a tubular flask seat carriage slidably mounted within said support and movable axially through 70
10 said muffle, and a tubular flask seat detachably nesting in said tubular carriage, said seat, carriage and support being suitably vented to permit the escape of moisture, gases and smoke therethrough.

15 10. A device of the class described comprising a support, an open-ended muffle mounted thereon, a flask seat carriage disposed axially of and shiftable through said support, a flask seat detachably connected 80
20 to the upper end of said carriage and adapted to support a flask with its contained investment, and means for raising and lowering the flask seat into and out of the muffle.

11. A device of the class described comprising a ventilated support, an open-ended muffle mounted thereon, a flask seat carriage disposed axially through said support, a vented flask seat disposed in the upper end 90
25 of said carriage, said carriage having a suitable number of vents communicating with the vents of said seat, and means for raising and lowering said seat with respect to said 95
30 muffle.

12. A flask seat for a device of the character described comprising a hollow vented shank having a laterally disposed disk-like support, said disk having an annular upstanding flange adapted to engage the walls of said flask, the bore of said shank connecting with the faces of said disk, said disk and flange also having a suitable number of vents.

13. A flask seat comprising a tubular shank vented and formed at its upper portion with a lateral disk having an annular upstanding flange adapted to form a seat for the flask, said flange and the upper face of said disk being suitably vented, the upper face of said disk communicating with the bore of said shank and a substantially thin disk of porous material superimposed on the upper face of said disk and lying within said flange.

14. A device of the character described comprising a support, an open-ended muffle mounted thereon, a flask seat carriage mounted on said base below said muffle and movable axially therethrough, a flask seal supported by said base and arranged above and axially of said muffle, and means for shifting said flask seat from a position within said muffle to flask seal contacting position.

15. A device of the class described comprising a base, an open-ended muffle sup-

ported thereon, a flask seat carriage and a flask seal supported by said base and located axially of said muffle below and above said muffle, respectively, means for moving said carriage into contact with said seal.

16. An apparatus of the character described comprising a base, a flask seat and a flask seal supported thereon, means for shifting said seal and seat relatively whereby the flask on said seat and the seal contact, automatic means for locking said parts in such position.

17. An apparatus of the character described comprising a base, a flask seat and a flask seal supported thereon, means for shifting said seat into yielding contact with said seal, means for giving said seat and seal an additional shifting movement whereby said flask is locked in seal engaging position, and means controlled by the yielding of said seal for altering the air pressure in said sealed flask.

18. An apparatus of the character described comprising a base, a flask seat and a flask seal supported thereon, means for shifting said seat with its supported flask into contact with said seal, means for giving said seat an additional shifting movement whereby said flask is locked in seal engaging position, said additional movement acting to admit fluid pressure into said flask for the purpose set forth.

19. An apparatus of the character described comprising a base, a flask seat movably mounted thereon, a flask seal yieldably mounted thereon and constructed and arranged to be moved by said flask seat moving means into a non-yielding position, and means brought into operation by said yielding movement of said seal for locking said seat against further movement.

20. An apparatus of the character described comprising a base, a flask seal mounted thereon, a flask seat formed with a slot carriage, means for moving said carriage toward said seal, and a spring actuated locking member operable to enter said slot in the carriage when said carriage is properly positioned with respect to said flask.

21. An apparatus of the character described comprising a base, a flask seal and flask seat mounted thereon, said carriage being formed with a slot, a locking member actuated to enter said slot in said carriage to lock the same from movement, said locking member being constructed and arranged to give said carriage an additional movement toward said seal prior to the locking of said carriage.

22. An apparatus of the character described comprising a base, a flask seat movably mounted thereon, a flask seal yieldably mounted against a rigid abutment on said base, said seal having a fluid pressure inlet,

a valve therefor, and means for moving said seat with the flask supported thereon into contact with said seal whereby said seal is shifted and said valve is opened to admit fluid pressure to said flask.

23. An apparatus of the class described comprising a support, a muffle mounted thereon, a flask carriage shiftable on said support, a flask seat on said carriage, means for shifting said carriage, a spring pressed 10 detent normally projected into the path of said carriage, said carriage having a slot therethrough to receive said detent whereby to lock said carriage in desired position.

15 24. A device of the class described comprising a base, an open-ended muffle supported thereon, a flask seal supported on said base in spaced relation to one open side of said muffle, a flask seat carriage supported on said base and movable from a heating position within said muffle to a flask 20 contacting position outside of said muffle.

25 25. A device of the class described comprising a support, an open-ended muffle thereon, a flask seal on said support and spaced from the open end of said muffle, and a flask carriage shiftable on said support from a position between said muffle and seal into heating and sealing positions, 30 respectively.

26. An apparatus of the character described comprising a base, a yieldable flask seal thereon, means controlled by the yielding of said seal for altering the working 35 pressure in said seal, a shiftable flask carriage provided with a locking slot, means for moving said carriage to shift said flask into contact with said seal, a spring pressed

detent adapted to enter said slot to lock said carriage in raised position, said slot and detent being constructed and arranged to give said carriage an extra movement toward said flask seal to operate the pressure controlling mechanism.

27. In a device of the character described, 45 a support, a shiftable flask seal thereon, fluid pressure controlling means operated by the shifting of said seal, a movable carriage having a groove and a slot therein, a flask seat thereon, means for moving said carriage, a spring pressed detent normally projected into said groove and adapted to enter said slot on movement of said carriage, and means for retracting said detent.

28. In a device of the character described, 55 a support, a shiftable flask seat thereon, a shiftable seal thereon provided with an air passage, a spring pressed valve in said passage normally closing the same, a source of air pressure connected to said passage, said 60 valve and seal being constructed and arranged so that on movement of said seal said valve will shift to open said passage.

29. In a device of the character described, 65 the combination of a support including an overhanging arm, an open-ended muffle on said support, a seal on said arm overhanging said muffle, a flask seat carriage carried by said support and shiftable axially through said muffle into contact with said seal, and means on said support for shifting said carriage.

In testimony whereof, I affix my signature.

CHRIS S. VAN HORN.
